CHARLES LUSTED, OF NEW YORK, N. Y.

Letters Patent No. 73,189, dated January 7, 1868.

IMPROVED SNOW-PLough.

The Schedule referred to in these Letters Patent and making part of the same.

TO ALL WHOM IT MAY CONCERN:

Be it known that I, CHARLES LUSTED, of the city, county, and State of New York, have invented a new and improved Snow-Plough; and I do hereby declare that the following is a full, clear, and exact description thereof, which will enable others skilled in the art to make and use the same, reference being had to the accompanying drawings, forming part of this specification, in which—

Figure 1 represents a longitudinal sectional view of my invention, the plane of section being indicated by the line $x x$, fig. 2.

Figure 2 is a plan or top view of the same.

Figure 3 is a side elevation, on a reduced scale, of the same.

Similar letters of reference indicate corresponding parts.

This invention relates to a new plough for clearing railroad-tracks from snow, and consists in the use of an oscillating ploughshare, which throws off the snow that has been raised by it, so as to prevent the accumulation of the snow upon the share. The oscillating share is hinged to a stationary lower share, and is connected with a crank on the axle of the truck, to which the device is secured. By means of a clutch-arrangement, the connection between the axle and the share may be established or interrupted at will, so that the upper hinged share may remain stationary, if desired.

A represents a truck, of suitable construction, mounted upon wheels in the ordinary manner, and arranged so that it can be secured to a train or locomotive, to clear the track in front of the same. On the front axle B, or on any one of its axles, are hung cranks, $a a$, which turn loose on the axle, but which can be made to revolve with the same by means of clutches, $b b$, fitted to levers $c c$, as shown. The levers are hinged to the track, and are operated by means of an oscillating lever, d , and intervening connecting-rods, e , or by any other suitable mechanism.

C is a metal ploughshare, secured firmly in front of the truck A, its most forward point being at one side of the apparatus, as shown in fig. 2. To the upper edge of this share C is hinged, by means of hinges f , another share, D, which forms a continuation of the former, so that the shares C and D do actually form but one single share of suitable height, and as wide as the road to be cleared is to be.

To the inner side of the hinged share D are secured lugs, $g g$, to which jointed connecting-rods h are pivoted, the lower ends of which are pivoted to the cranks $a a$, as is clearly shown in fig. 1.

When the cranks are thrown in gear with the clutches, and when the truck is moving, the share D will thus be oscillated around its pivot, the extremes of its position being indicated in fig. 3 by red and black lines. Thus, as the truck is pushed through the snow, the latter will rise on the share C D, and would accumulate thereon, preventing the further progress of the truck, if the share D would not, once during every revolution of the axle B, swing forward, thereby not only throwing off the snow that had accumulated on it, but also casting it aside, owing to the oblique position of the share. The track will thus be effectually cleared from the snow, and it will require comparatively little power to force the truck ahead.

The snow-ploughs now in use are ineffective in heavy snow, as they raise the snow without casting it aside, while those snow-ploughs which melt the snow glaze the rails in such a manner that they are unsafe for use as long as the ice remains upon them.

To the sides of the share D are secured flanges, $i i$, which fit over the side plates of the truck, to close the opening between the front end of these plates and the share D, when the same is swung forward. The snow is thereby prevented from falling upon the working-mechanism of the truck.

For single-track roads, the share C may be made pointed, that is, with its forward part in the centre, so as to throw the snow to both sides. In that case, the share D must be composed of two pieces, which meet in the centre.

Having thus described my invention, what I claim as new, and desire to secure by Letters Patent, is—

1. The hinged oscillating ploughshare D, when made and operating substantially as and for the purpose herein shown and described.

2. A snow-plough, provided with an oscillating share, D, which is hinged to the upper edge of a stationary share, C, and which has flanges, $i i$, at the ends, substantially as herein shown and described.

3. The hinged share D of a snow-plough, connected by means of a jointed rod or rods, g , with a crank or cranks, x , on the axle of the plough-truck, as described, the crank or cranks being loose on the axle, and connected with clutches, so that the share can be made to oscillate or not, as set forth.
